(57) **CLAIM**

The ornamental design for a camera for mobile phone as shown and described.

DESCRIPTION

FIG. 1 is a front, top perspective view of a camera for mobile phone showing my new design;

FIG. 2 is a rear, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, top perspective view thereof shown in a configuration of use; and,

FIG. 10 is a top perspective view thereof shown recessed in a mobile phone.

The broken lines in the drawings depict portions of the camera for mobile phone that form no part of the claimed design. The dash-dot-dash broken lines in the drawings depict boundary lines around areas that form no part of the claimed design.

1 Claim, 10 Drawing Sheets(56)
